W. N. LINDSEY.
DRAIN VALVE FOR WELL PIPES.
APPLICATION FILED JUNE 22, 1917.

Patented May 21, 1918.

ATTORNEY

UNITED STATES PATENT OFFICE.

WILLIAM NOAL LINDSEY, OF CLAUDE, TEXAS.

DRAIN-VALVE FOR WELL-PIPES.

1,267,093.

Specification of Letters Patent. Patented May 21, 1918.

Application filed June 22, 1917. Serial No. 176,396.

To all whom it may concern:

Be it known that I, WILLIAM N. LINDSEY, a citizen of the United States, residing at Claude, in the county of Armstrong and State of Texas, have invented certain new and useful Improvements in Drain-Valves for Well-Pipes, of which the following is a specification.

This invention relates to drain valves, and 10 is adapted particularly for use in connection with well pipes.

The primary object of the invention is to provide a drain valve adapted to be positioned in the stand pipe of a well below the 15 surface of the ground, and which may be actuated in cold weather so as to permit of the water in the pipe being drained back into the well, whereby danger of injury to the pumping apparatus or bursting of the 20 pipes by freezing will be obviated.

A further and particular object of the invention is to provide a drain apparatus of the character mentioned, which is capable of being readily applied to the well pipe 25 at the desired place, and which requires no specially constructed pipe or apparatus for its installation.

Still further objects reside in providing an apparatus of the character described 30 which is of extremely simple and inexpensive construction, which is positive in its operations, which involves comparatively few movable parts, the various parts being so constructed and assembled as to minimize 35 the opportunity for wear, breakage or derangement of the same, which is easy of operation, and which will prove thoroughly practical in use.

With these objects in view together with 40 others which will appear as the description proceeds, the invention resides in the novel formation, combination and arrangement of parts, all as will be described more fully hereinafter, illustrated in the drawings, and 45 particularly pointed out in the claims.

In the drawing:

Figure 1 is a side elevation of a portion of a conventional form of well pipe, and illustrating the application of a drain valve 50 and operating means constructed in accordance with the invention,

Fig. 2 is a similar view, parts broken away, and illustrating the movable parts of the valve and actuating mechanism in changed position, 55

Fig. 3 is an enlarged detail perspective view of the locking arm used in carrying out the invention,

Fig. 4 is an enlarged transverse sectional view taken substantially upon line 4-4 of 60 Fig. 2, and

Fig. 5 is a detail perspective view of the bell-crank lever which actuates the drain valve.

Referring now to the drawing, 6 indicates 65 the stand pipe of a well, the said pipe being made of a plurality of pipe sections. This pipe extends down into the water of the well at its lower end, and the upper end of the said pipe projects above the ground, and 70 well pipes of this character are usually provided with a longitudinally reciprocable sucker rod which carries at its lower end the pump piston. The sucker rod and plunger or piston forming no part of the invention, 75 are not illustrated in the drawing.

The invention comprehends a valve adapted to be positioned in the stand pipe of the well below the ground surface, and which may be actuated when desired to drain the 80 water standing in the pipe. In carrying out the invention, the valve is arranged in a relatively short pipe section indicated at 7, so that this section may be readily interposed between the adjacent ends of any of 85 the main pipe sections. The section 7 is inclosed by a metallic strap indicated at 8, upon which a substantially U-shaped support 9 is secured, and within which is pivoted at 10 a valve stem 11. This stem 11 is 90 bent at right angles at its lower end as shown, and carries a valve head 12 at the end of the angularly disposed portion. This valve head is adapted to bear against and seat over a valve or drain opening 13 in the 95 pipe section 7. If desired, the head 12 may be equipped with a washer or gasket 14, so as to preclude the escape of water from the pipe when the valve is seated. The strap member 8 also confines between itself and 100 the member 7 a vertically disposed strap 15, to the upper end of which an outwardly ex-

tending arm 16 is secured. Pivoted as at 17 to this arm is a bell-crank lever 18, the extremities of one of the arms of which is provided with a laterally extending finger 19, which rests within a recessed portion 20 in the outer surface of the upper end of the valve stem 11. An expansion spring 21 is interposed between the strap member 15 and the upper end of the valve stem 11, and this 5 spring holds the valve normally closed. The valve stem and strap member 15, may if desired, be provided with lugs which project into the coil spring 21, so that the latter will be held in proper assembled position upon 10 the section 7.

The actuating means for the valve is positioned preferably in a position convenient for the manipulation of an operator, and this actuating mechanism is secured to a 20 clamp member 25 encircling and secured to the pipe 6 above the surface of the ground. This clamp member has secured to one side thereof an upwardly extending metallic plate 26, from the upper end of which an 25 angularly and outwardly extending locking arm 27 projects. This arm 27 is recessed as at 28 on one side, and this recessed portion is adapted to accommodate the actuating lever 29 pivoted as at 30 upon an 30 outwardly extending ear 31 carried by the clamp member 25. The locking arm 27 is so positioned with relation to the outwardly extending ear 31 that lateral springing of the lever 29 is required to engage the lever 35 within the notch 28, or to disengage the lever from the locking arm. The lever 29 is provided upon one side with an outwardly extending stud 32, to which one end of a connecting rod or link 33 is secured, the opposite end of the said rod being secured to a stud 34 projecting outwardly from the 40 upper arm of the bell-crank lever 18.

It will be observed, particularly with reference to Fig. 1 of the drawing, that the 45 pivot 30 supporting the lever 29 is located in a vertical plane beyond the vertical plane of the stud 34 of the bell-crank lever 18, and therefore when the lever 29 is moved inwardly into locking engagement within the 50 notch 28, the stud 32 will have passed beyond a dead center through the stud 32, pivot 30, and bell-crank lever stud 34. This particular arrangement constitutes an efficient locking means for the actuating lever, 55 as it will be necessary to overcome this dead center before the actuating lever can be moved to releasing position.

After a device of my invention has been properly installed in a well pipe, and it is 60 desired to actuate the pump within the pipe, the lever 29 is disengaged from the locking arm 27, whereupon the spring 21 moves the valve head to seated position. When so

positioned, no water can escape from the interior of the pipe. When it is desired to 65 drain the water standing in the pipe, the lever 29 is moved upwardly and inwardly, until locked within the notch 28 of the locking arm 27. This operation of the locking lever rocks the bell-crank 18 so that the 70 finger 19 thereof moves inwardly, carrying with it the inner of the upper end of the valve stem 11. This movement of the valve stem 11 causes the head 12 to move away from the pipe section 7, whereupon the 75 port or opening 13 will be uncovered, so that the water within the pipe may drain therefrom.

It is obvious from the foregoing that I have provided an extremely simple and 80 thoroughly efficient means for carrying out the objects of the invention. The simplicity of the valve and controlling means therefor enables the same to be easily and positively actuated, and danger of breakage or 85 arrangement of these parts will be reduced to a minimum.

While the present is a disclosure of the preferred embodiment of the invention, it is to be understood that the invention is not 90 limited thereto, as various changes in the minor details of construction, proportion and arrangement of parts may be resorted to if desired without departing from the spirit 95 of the invention as defined by the appended claims.

What is claimed is:

1. The combination with a pipe, of a valve in said pipe, a spring tending normally to hold said valve in seating position, 100 a bell-crank lever, a finger on said lever engaged with said valve, an operating lever, and a connection between said lever and said bell-crank lever whereby operations of said lever will force said valve against the 105 tension of said spring.

2. The combination with a pipe, a bearing member on said pipe, the said pipe being provided with an opening, a valve stem pivoted in said bearing member, a head on said valve stem adapted to seat over said opening, a spring for normally holding said stem in valve closing position, a bell-crank lever, a finger on said lever engaged with said stem, an operating lever, and a connection between said operating lever and said bell-crank lever for moving said valve stem against the tension of said spring. 115

3. The combination with a pipe having an opening therein, a bearing member carried by said pipe, a valve stem pivoted in said bearing member, a head carried by one end of said stem for seating over said opening, an arm on said pipe, a bell-crank lever pivoted upon said arm, a finger on one of 120 the arms of said bell-crank lever disposed

in the path of travel of said valve stem, a
spring tending normally to force said stem
in valve closing position, a lever pivoted to
said pipe, and a link connecting said lever
5 with the opposite arm of said bell-crank
lever.

In testimony whereof I affix my signature
in presence of two witnesses.

WILLIAM NOAL LINDSEY.
